Specification of Letters Patent

Patented May 12, 1914.

Application filed November 15, 1912. Serial No. 731,506.

To all whom it may concern:

Be it known that I, JOHN H. BARR, citizen of the United States, and resident of the borough of Manhattan, city of New York, in the county of New York and State of New York, have invented certain new and useful Improvements in Type-Writing Machines, of which the following is a specification.

My invention relates to carriage feeding or escapement devices for typewriting machines and its principal object is to provide improved devices of the character specified.

To the above and other ends my invention consists in the features of construction, combinations of devices and arrangements of parts hereinafter described and particularly pointed out in the claims.

Two main forms of my invention with changes of detail are illustrated in the accompanying drawings, wherein—

Figure 1 is a vertical front to rear sectional view of so much of a typewriting machine as is necessary to illustrate my invention. Fig. 2 is an enlarged detail view of the releasable connection between the carriage feed rack and the escapement wheel shaft. Fig. 3 is a detail side elevation partly in section, the section being taken on the axis of the escapement wheel. Fig. 4 is a horizontal sectional view taken on the line *a* in Fig. 3 and looking in the direction of the arrow at said line. Fig. 5 is a fragmentary elevation of the escapement wheel and associate parts looked at from the front. Fig. 5^a shows a modified connection between said escapement wheel and the carriage. Fig. 5^b shows a further modification of such connection. Fig. 6 is a fragmentary front to rear vertical sectional view of a typewriting machine embodying a form of my invention different from what is shown in the preceding figures. Fig. 7 is a fragmentary detail view showing a front elevation of the Fig. 6 form of the invention. Fig. 8 is a fragmentary side elevation, partly in section, of Fig. 7. Fig. 9 is a perspective view of certain of the actuating devices shown in Fig. 6. Figs. 10 and 11 are sectional views of the escapement wheel shown in Fig. 6, the sections being taken respectively transversely of said wheel and axially thereof. Fig. 12 is a detached view of a detail of the Fig. 6 form of the invention.

Fig. 13 is a fragmentary face view of a part or cover of the escapement wheel shown in Fig. 6.

Referring first to the form of the invention shown in Figs. 1 to 5 inclusive, the main frame of the machine as appears from Fig. 1 comprises a base 1, posts 2 and a top plate 3, above which is supported a stationary trackway 4 connected through anti-friction balls 5 with the rear or slide bar of a carriage 6 on which is rotatably supported a platen 7. Adapted to coöperate with the front face of the platen are a set of type bars, each type bar 8 being fulcrumed at 9 on a support 10 and connected through a link 11, bell crank 12 and second link 13 with a printing key lever 14 which is fulcrumed at 15 in the rear portion of the base and is provided with a restoring spring 16. Secured to posts 17 depending from the carriage 6 is a feed rack 18 that coöperates with a feed pinion 19 loosely mounted at the upper end of a vertical shaft 20 that bears at its ends in stationary pivot pins 21—22 secured respectively in the top plate 3 and in the base 1. The upper end portion of the shaft 20 on which the pinion bears is reduced in diameter and the pinion rests on the shoulder formed between this reduced portion and the body of the shaft, being prevented from rising or moving upward lengthwise of the shaft by a collar 23 fixed to the reduced end portion of the shaft. As clearly shown in Fig. 2 the hub portion 24 of the pinion is provided with one or more downwardly projecting ratchet teeth 25 which normally engage with crown ratchet teeth 26 formed on the upper face of a clutch member 27 which is provided with a slot 28 coöperating with a radial pin 29 on the shaft 20. A coiled spring 30 confined between the clutch member 27 and a collar 31 fixed to the shaft below said member constantly presses the clutch member upward and normally maintains the ratchet teeth 26 engaged with the tooth or teeth 25 on the pinion 19, thus normally connecting the pinion with the shaft 20. The clutch member 27 may be lowered along the shaft 20 against the pressure of the spring 30 by any suitable releasing means (not shown), thus disconnecting the pinion 19 from the shaft 20 and releasing the carriage so that it may have a free or continu-

ous leftward movement under the pull of its motor or spring drum 32 which is connected to the carriage by a strap 9.

The shaft 20 being the escapement wheel shaft is normally controlled by novel escapement devices which prevent free or continuous movement of the carriage except when it is released as described. The novel escapement devices comprise a rotary element or escapement wheel 33 which is suitably secured to the shaft 20 near its lower end as by a cross pin 33* (Fig. 3). The cross pin passes through the hub portion 34 of said escapement wheel which further comprises horizontally disposed flanges or guide portions 35 preferably integral with the hub portion. The lower end of the hub portion is reduced as indicated at 36 and receives an annular disk or supporting shelf 37 which is suitably secured in place. The teeth with which escapement wheels are ordinarily provided are replaced in the present instance by movable elements in the form of headed pins 38. These pins are vertically disposed and are arranged in parallelism in a circular series, being slideable up and down in holes or bearing openings in the flanges 35 and being also free to rotate therein on their own axes. The disk-like heads or enlargements 39 at the lower ends of the pins normally rest near their inner edges on the supporting shelf 37 and gravity tends to maintain them thus supported. There are twelve of these parallel pins or relatively movable teeth shown in the present instance but, of course, the number may be varied to suit the occasion. The pins are adapted to coact successively with a fixed arresting means, abutment or bracket 40 having a horizontal ear 41 secured by screws 42 to the upper rear portion of the base 1 at the left of the escapement wheel (Fig. 4). The bracket extends rightward in front of the escapement wheel and its upper edge is formed with a lug 43 projecting upward and having a vertical right-hand face 44 which is adapted to serve as an abutment or stop proper in cooperation with the left sides of the pin heads 39. The stop face 44 is in a line with the axis of the operative pin, which line is contained substantially in the path of rotation of said axis, and consequently as said stop face coacts with the heads 39 it will act as a positive stop for the arrest of the escapement wheel. In order to provide for the escapement or step-by-step advance of the wheel and of the platen carriage connected thereto and controlled thereby, means are provided under the control of the printing keys for successively lifting the pins or moving them upward longitudinally when they are in contactive engagement with the stop face 44 so as to free the escapement wheel and permit it to be turned until the next succeeding pin 65 engages with said stop face or arresting

means. Said means in the present instance comprises an actuator or lifting device 45 vertically disposed and adapted to underlie the head 39 of the engaged or operative pin 38, the right-hand face of said actuator being beveled at its upper portion as indicated at 46 to provide an inclined or cam surface. The lower end portion of the actuator is bifurcated and straddles the rear end of a lever or rocker 47, being pivotally connected to said lever at 48. The lever or rocker 47 is provided with a hub or barrel portion 49 as clearly shown in Fig. 4, said barrel portion being pivoted at its ends on pivot pins 50 secured by screws 51 in arms 52 rigid on the base 1 and extending forward from the rear portion thereof. As shown in Fig. 1 the forward arm of the lever 47 is connected by a link 53 with a universal bar 54 supported on pivoted arms 55 and underlying the key levers, each of said key levers being adapted to actuate said universal bar and through it the lever 47 and actuator 45. A coiled restoring spring 56 connected at one end to a pin 57 on the lever 47 and at the opposite end to the bracket 40 assists to maintain the lever and connected parts in normal position and to restore them thereto after operation. A leaf spring 58 secured by a screw 59 to the lever 47 extends rearward under said lever and its free end cooperates with the lower or bifurcated portion of the actuator 45, tending constantly to throw the upper part of said actuator rearward on its pivot and normally maintaining said actuator in contact with the bracket 40 which serves as a stop therefor. An arm 60 secured by a screw 61 (Fig. 4) to an extension 62 rigid on the base 1 extends transversely of the rear arm of the lever 47 underlying the spring 58 and serves as a stop for the lever 47 and connected parts, assisting to maintain said lever and parts in normal position. A camming or restoring device or means independent of the escapement wheel is provided for insuring the restoration of the pins to normal position in contact with the support 37 and in line with or in the plane of the arresting means or stop face 44 just prior to co-operation with said stop face. Said device comprises an upright arm 63 suitably secured to the right-hand end of the bracket 40 as shown in Fig. 5, said arm terminating in a double ended cam 64 which lies in the path of the upper ends of the pins 38 when the latter are raised from their support 37, and is of sufficient stiffness to cam said pins downward and restore them to engagement with the support 37 during the turning movements of the escapement wheel.

In operation, assuming one of the pins to be engaged with the stopping face 44 as illustrated, then an actuation of any one of the printing key levers 14 or the space bar 130

(not shown) will operate to lower the universal bar and swing the lever 47 on its fulcrum, the rear arm of said lever swinging upward and causing the top of the actuator 45 to engage with the bottom of the overlying head 39, lifting said head and causing the pin to slide upward transversely of the plane of rotation of the wheel. As soon as the head has been lifted far enough to clear the stop face, or arresting means 44, that is, to the dotted line position in Fig. 5, the carriage motor spring, acting through the connected parts as described, will draw the carriage leftward and turn the escapement wheel until the next head 39 to the right of the head just lifted will contact with the stop face. The parts are so proportioned and adjusted that this movement of the escapement wheel corresponds to a letter space movement of the carriage. On releasing the actuated printing key lever the lever 47, actuator 45 and connected parts will be restored to normal position. Should the advancing head 39 move so rapidly that it contacts with the actuator 45 before said actuator has been lowered out of its path, the full letter space movement of the wheel will nevertheless not be prevented for the advancing head will act against the cam face 46 and overcoming the spring 58 will force the upper portion of the actuator 45 forward about its pivot 48 and out of the path of the advancing head 39 which will continue to move until it contacts with the stop face 44. As soon as the rear arm of the lever 47 is swung downward far enough to lower the actuator 45 below the head 39, the spring 58 will operate to swing the actuator rearward on its pivot into contact with the bracket 40. It will be understood that at each repetition of the operation above described, the carriage will advance a letter space and the escapement wheel will turn a distance corresponding to that between any two of the pins. In ordinary operation after the pin has been lifted above the stop face 44 and escapes leftward past the lug 43, it will drop down to normal position again through the force of gravity; but should the pins for any reason stick in elevated position, then as the wheel is turned and they again approach the operative position, the tops of such pins as may be elevated will contact with the right-hand upturned end or cam of the cam piece 64 and will be forced or cammed downward thereby transversely of the escapement wheel and into contact with the supporting shelf 37.

In practice the construction above described may be simplified by dispensing with the clutch mechanism comprising the spring-pressed member 27, and securing the feed pinion permanently to the escapement wheel shaft. In such case in order to release the carriage the engaged pin-head 39 may

be separated from the abutment or arresting means by a relative movement of the parts transverse of the escapement wheel. This may be accomplished either by raising the escapement wheel bodily so that the pin-heads will clear the abutment or else by lowering the abutment out of the path of the pin-heads. These modifications are illustrated respectively in Figs. 5^a and 5^b.

In Fig. 5^a the escapement wheel shaft 20 is replaced by a shaft 200, the ends of which are reduced and fit in bearing openings in the base 1 and top plate 3, these reduced ends coöperating with balls 201 and 202. The lower ball 201 bears on an adjustable screw-pin 203 which is fixed in the base while the upper ball is held down by a headed pin 204 the head of which normally rests on a boss 3^a on the top plate and is maintained thereagainst by a leaf-spring 205. Motion is transmitted to the shaft 200 from the feed rack 18 by a feed pinion 206 which is fixedly secured to the shaft 200 as by a cross pin 207 passing through the hub of said pinion. The escapement wheel supporting the pins 38, 39 is fixed to the shaft as before and the heads 39 of said pins are adapted to coöperate with a vertical stop face 208 on a lug 209 rigid with a bracket 210 fixed to the base 1. The opposite face of the lug is inclined as indicated at 211. Pivoted at 212 to the bracket 210 is an arm 213 provided with a double cam 214 which is adapted to coöperate with the tops of the pins 38 to insure the proper positioning thereof. The tail 215 of the arm 213 extends downward and is normally maintained against a stop pin 216 on the bracket 210 by a spring 217 which surrounds the pivot 212. The shaft 200 may be lifted by devices operated from a key-controlled bar or bail 218 on the carriage. Said devices comprise a lever 219 having a fixed pivot 220, one arm of said lever being provided with a pin 221 which is adapted to be engaged by the key-operated bar 218, and the other arm of said lever being forked or bifurcated to loosely embrace the hub of the pinion 206, the forks or bifurcations 222 curving upward and being adapted to contact with the under face of the pinion 206.

In operation, when the carriage is returned from left to right the pin heads 39 will successively ride up the inclined face or cam 211 and drop down in front of the lug 209 so that the return movement of the carriage is free and unobstructed. When it is desired to release the carriage for movement from right to left, the bar or bail 218 may be depressed as by operating its associate release key, this depression in turn actuating the lever 219 which acts against the pinion 206 to move the shaft 200 upward longitudinally, the spring 205 yielding for this purpose. This upward movement of

the shaft is so limited that its lower reduced end will not disengage from its bearing opening in the base 1; but it is sufficient to enable the pin heads 39 to clear the arresting or stop face 208, and consequently the carriage may advance freely and uninterruptedly, the pin heads 39 turning in a plane above the top of the lug 209. On releasing the actuated bar 218 the parts will 10 return to normal position, this return being assisted by the spring 205.

In the Fig. 5^a construction, the shaft 200 is provided with a fixed bearing at the top as well as at the bottom so that it is held 15 against longitudinal movement in either direction. The pin heads 39 in this construction coöperate with a lug 223 integral with a horizontal arm 224 pivoted at 225 on a standard 226 stationary on the base 1. A 20 cam member 227 is also secured to said standard and is provided with a cam 228. A coiled spring 229 connected at its ends respectively to the pivoted arm 224 and the member 227 normally maintains the free 25 end of said arm 224 engaged with a fixed stop 230. This arm is controlled by a suitable train of key actuated devices beginning with a key (not shown) on the carriage and terminating with a link or member 231, the 30 lower end of which is pivoted at 232 to the arm 224 near its free end. When said release key is actuated the member 231 is lowered, swinging down the arm 224 against the spring 229 and lowering the arresting 35 device or abutment 223 out of the path of the pin heads 39 so that the shaft 200 is free to rotate and permit a continuous leftward movement of the carriage.

It may be noted that in the Figs. 1-5 construction the back of the lug 43 is inclined so that the pin heads 39 may ride up over the lug as in the Fig. 5^a and Fig. 5^b constructions.

The second of the principal forms of the 45 invention herein illustrated is shown in Figs. 6 to 12 inclusive, the invention here being applied to a vertically disposed escapement wheel having a horizontally arranged axis or shaft instead of to a horizontal escapement wheel having a vertical axis or shaft as in the first described construction. The typewriting machine illustrated in Fig. 6 has a main frame comprising side plates 65 connected by a top plate 66 above which is 50 mounted a stationary track-way 67 connected through anti-friction balls 68 with a carriage 69 supporting a platen 70 with the front face whereof coöperate type bars 71 pivoted at 72 and each connected through a 55 train of devices comprising a link 73, a toggle element 74, a second link 75 and a bell crank 76 with a key stem 77 provided with a key 78. The toggle elements 74 are each fulcrumed as at 79 on a fixed support 80 and 60 are provided with restoring springs 81. The

tail portions 74^a of the toggle elements are adapted to actuate a curved universal bar or member 82 which is vertically disposed and is pivotally connected at about its middle at 83 to an arm 84 on a rock shaft 85. 70 At its sides said member 82 is connected by ears 86 with arms 87 rigid on a rock shaft 88 which rock shaft is connected to the rock shaft 85 in the usual or any other suitable way. Fixed to this rock shaft is an 75 upwardly extending arm 89 which is bent rearward at its upper end and terminates in a vertically disposed operating face 90 (Fig. 8). The carriage 69 is provided with a feed rack 91 with which mesh a pair of gear 80 wheels 92 and 93 arranged face to face and having a lost motion connection as in the Smith Premier No. 10 machine which this part of the construction generally resembles.

The gear wheel 92 is suitably connected 85 with the usual carriage motor or spring drum 94 and the gear wheel 93 meshes with a pinion 95 which is loosely mounted on a horizontal shaft 96 extending fore and aft of the machine, said shaft bearing at its 90 ends in pivot pins 97. The rear pivot pin 97 is supported on the spring drum casting 98 while the forward pivot pin is supported on a bracket 99 secured by screws 100 to a plate 101 fast on the casting 98, the shaft passing 95 freely through an enlarged opening 101^a in said plate (Fig. 8). The pinion 95 is provided with a hub 95^a which abuts a washer 102 that engages with a novel escapement wheel hereinafter described and thus prevents forward movement of the pinion 95 100 along the shaft 96. Said pinion is provided with crown ratchet teeth which normally engage with corresponding ratchet teeth on a clutch member 103. Said clutch member is 105 provided with fingers 104 which engage with notches formed in a flange 105 on the shaft 96. A coiled spring 106 is confined between the flange 105 and the head of the clutch member 103 and constantly presses the teeth 110 of said clutch member into engagement with the crown ratchet teeth of the pinion 95. Suitable releasing means (not shown) are provided for moving the clutch member 115 rearward and disconnecting the gear wheel 110 93 from the shaft 96 so that the carriage may move freely leftward under the action of the spring drum. Ordinarily, however, the carriage is connected with the shaft 96 as described and said shaft is controlled by escapement devices which are operative from the universal bar 82. These escapement devices comprise an escapement wheel 107 arranged on the shaft 96 between the plate 101 and the bracket 99. Said wheel comprises 120 (as clearly appears from Fig. 11) a hub or barrel portion 108 integral with which is a ratchet wheel 109 coöperative wherewith is a spring-pressed back pawl 110 of the usual construction (Fig. 7). The hub is bored out 125 130

as indicated at 111 to fit over the shaft 96 to which it is secured by a set screw 112 that is received in a tapped hole in the hub and abuts against the shaft 96. Secured to the 5 forward face of the ratchet wheel 109 by any suitable means is a dished plate 113 the periphery of which is formed with a series of notches 114 (Fig. 13). The forward end of the hub 108 is slightly reduced as indicated at 108^a and receives a plate 115 which is provided with a series of tongues 116, said tongues being turned rearward at right angles to the plane of the plate and fitting into the notches 114 in which said tongues 10 are suitably secured. The plates 115 and 113 provide in effect a hollow box in the periphery of which are a series of rectangular openings or slots 117 formed by the spaces between the tongues 116, said box being secured in rigid relationship with the hub 20 portion 108 and acting therewith as a single member or escapement wheel. Said wheel is provided with relatively movable teeth or elements in the form of fingers 118, these 25 fingers, of course, being arranged in place before the parts 113 and 115 of the box are assembled. Said fingers as may be seen from Fig. 10 are shaped somewhat like key stones and are radially arranged, each having at its 30 inner end a rounded teat 119 which fits loosely in a round guide hole 120, the series of guide holes 120 being formed radially in the front end portion of the hub 108 to the rear of the reduced end 108^a. The outer end 35 portions of the fingers 118 are reduced as indicated at 121, these reduced portions forming with the body portions shoulders 122 and projecting radially outward through the openings 117. These reduced portions 121 40 are rectangular in cross section and provide a series of relatively movable escapement teeth. As will be understood from Fig. 11 the fingers or toothed members 118 are adapted to swing to a limited extent fore 45 and aft of the machine within their receptacle or box 113, 115, owing to the fact that the part of the box farthest from the center is of somewhat greater depth than the height of the toothed members due to the 50 dishing of the cover plate 113. During the swinging movements of the members 118, the purpose of which is to provide for the escapement or step-by-step turning movement of the escapement wheel and parts controlled thereby, the shoulders 122 will slide back and forth over the inner faces of the tongues 116 adjacent the openings 117 in which openings the teeth proper 121 may move freely back and forth transversely of 55 the plane of rotation of the escapement wheel while the inner ends of the toothed members 118 are controlled by the guiding teats 119, the result being that the members 118 are in effect loosely pivoted in their 60 plane of rotation of the escapement wheel while the inner ends of the toothed members 118 are controlled by the guiding teats 119, the result being that the members 118 are in effect loosely pivoted in their 65 containing element or holder. Twelve of

these toothed members 118 are shown in the present instance but, of course, the number may be varied to suit the particular conditions of the construction in hand.

As in the prior construction the movable teeth are adapted to co-act with a fixed arresting means or abutment which is shown detached in Fig. 12, said means being in the form of a plate 123, the right-hand end of which provides a vertical stopping face 124 in the path of the teeth and for engagement thereby. The plate 123 is provided with an enlargement 125 which is secured by a headed screw 126 to the plate 101. A dowel pin 127 projects forward from the plate 80 through a hole in the enlargement and assists to prevent displacement of the plate 123. Said plate is off-set forward from the enlargement 125, as will be understood from Fig. 8, so as to be in the plane of rotation of 85 the teeth 121 when these are in operative position at the forward ends of the slots 117. In order to insure that the teeth are in line with, or in the plane of rotation of, the stop 123 as they near it during the rotation of the element or wheel 107, a camming member or means 128 separate from said wheel is provided, said camming member being secured as by rivets 129 to the stop 90 123 and its free end being curved or flared 95 rearward to provide a cam surface to engage the teeth 121 when they are at the rear ends of the slots 117, said surface operating to cam or swing the teeth forward as the wheel is rotated in the direction of the arrow in 100 Fig. 7. In order to disengage the teeth successively from the arresting means or face 124 so as to provide for a step-by-step escapement of the escapement wheel, devices are provided comprising a pusher or actuator 130 horizontally disposed and pivoted at 131 at its forward end to a rocker member 132 which is best shown in Fig. 9. This rocker member comprises a crank arm portion 133 to which the actuator 130 is pivoted, 110 and a hub portion 134 which is suitably secured to a rock shaft 135, the ends whereof are pivoted on adjustable screw pivots 136 supported in ears 99^a projecting downward from the bracket 99. The hub portion 134 is provided with a leftward extension 137 having an enlargement 138 in which is secured a pin 139, the pin extending laterally rightward parallel with the extension 137 above the same, said pin being adapted 120 to be actuated by the operating face 90 on the arm 89. These parts are normally separated as shown in Fig. 8. A coiled restoring spring 140 is secured at its forward end to a stationary pin 141 on the left-hand ear 125 99^a and at its rear end to the pin 139. The somewhat intricate character of the rocker member 132 is necessary in the present case to avoid interference with other parts. The actuator 130 is normally held up against a 130

stop 142 on the rocker member by a wire spring 143. Said actuator passes rearward over a cut-out 128* in the cam device 128 and its rear end normally lies just in front 5 of the operative tooth 121. The right-hand side of the actuator is cut away to provide an inclined or cam face 130*. The actuator is constantly acted on by the spring 140 which through the rocker 132 tends to draw 10 said actuator forward, but this movement is controlled by stop devices comprising a stop pin 144 curving downward and rearward from the actuator 132 below its pivots and contacting with an adjustable screw-stop 145 15 secured to an ear 101^b on the plate 101 (Figs. 6 and 8).

In operation, an actuation of one of the printing keys 78 acting through the toggle element 74 will move the universal bar 82 20 rearward and turn the rock shaft 83, causing the operating face 90 to swing rearward and contact with the pin 139, thereby swinging the rocker 132 rearward and causing the actuator 130 to push the operative tooth 121 toward the rear. This tooth it 25 will be understood is maintained by the carriage motor or spring drum in engagement with the stop face 124 and as soon as said tooth has moved rearward transversely of 30 the escapement wheel far enough to disengage from said stop face, the spring drum will operate to turn the wheel and cause a letter space movement of the carriage, the wheel being arrested by the engagement of 35 the next succeeding tooth 121 with the stop face 124. If the actuator should fail to swing bodily forward out of the path of the advancing tooth 121, the edge of said tooth acting against the cam face 130* will cam 40 the actuator 130 downward, said actuator swinging on its pivot 131 independently of the rocker out of the path of the advancing tooth which will move on until arrested by the stop face 124. As soon as the actuator 45 has swung forward out of contact with the tooth 124 it will be thrown upward on its pivot 131 by the spring 143 and will be in position at the next key actuation to contact with the front face of the engaged tooth 50 121 to disengage the same and permit a second letter space advance movement of the carriage. The teeth 121 after being successively moved out of the path of the stop face 124, will under ordinary conditions re- 55 main swung rearward in contact with the plate 113 as shown at the upper part of Fig. 11 until the rotation of the escapement wheel brings said teeth into co-action with the cam member 128 which will operate to 60 swing the tooth forward into engagement with the plate 115 as shown at the lower part of Fig. 11 at which time the tooth will be in register or line with the stop 124.

Among the advantages obtained from my

present invention it will be observed that it 65 provides for a full drop, the carriage moving the full letter space distance during the movement of a printing key in one direction. Another advantage is that the invention does away with the liability of skipping, 70 which is a defect common to escapement mechanism particularly under rapid operation. By interposing a positive fixed abutment or arresting device in the path of the teeth it is impossible to obtain an accidental 75 or undesired advance movement by reason of the abutment being pushed or cammed out of the way. The only manner in which an advance can be had is by moving the co-acting part, that is, the tooth of the escapement wheel, itself, and to do this a key 80 operation is necessary. A third chief advantage is that I obtain uniformity in the timing of the escapement. In prior constructions, owing to the warping of the escapement wheel itself, or to looseness in its mounting, it is impossible to avoid some variation in timing so that the let-off will take place at one time during the key stroke when one of the escapement wheel teeth is 85 in operation, and at another and different time in a succeeding key stroke when another tooth is in operation. By employing in the present instance a single actuator and a single arresting device it is obvious 90 that the timing of the escapement will always be the same no matter which of the movable teeth is in operation, for even though the time at which the different teeth are picked up by the actuator and consequently the extent of a movement of said teeth may vary slightly, nevertheless, the time at which the teeth are moved out of 95 engagement with the arresting means will always be the same.

100 Variations other than those described may be effected within the scope of my present invention and without departing from its principles. It will be understood, for example, that though the escapement devices 110 herein shown are arranged for a "reverse feed," that is, to permit the carriage to feed on the down stroke of the keys, yet they may readily be adapted for the "ordinary" feed in which the carriage advances on the re- 115 turn stroke of the keys.

120 The second form of the invention illustrated in Figs. 6 to 13 is not claimed specifically herein, as specific claims to said second form are made in a divisional application relating to said second form.

125 What I claim as new and desire to secure by Letters Patent, is—

1. In carriage feeding mechanism for typewriting machines, the combination of an element provided with a plurality of relatively movable teeth, means co-operating successively with said teeth to arrest the car-

riage, and a key controlled actuator for moving said teeth out of engagement with said means, said teeth at times exercising a camming effect on said actuator during movement of said element.

2. In carriage feeding mechanism for typewriting machines, the combination of an element provided with a plurality of relatively movable teeth, means coöperating successively with said teeth to arrest the carriage, and a key controlled actuator for moving each tooth out of engagement with said means, the next succeeding tooth to the one moved being operative to cam said actuator out of its path during the movement of said element resulting from the operation of said actuator.

3. In carriage feeding mechanism for typewriting machines, the combination of an element provided with a plurality of relatively movable teeth, a coöperating abutment, a key controlled support, an actuator pivoted on said support, and a spring for said actuator, said actuator after moving one tooth out of operation being itself movable by the next succeeding tooth out of its path.

4. In a typewriting machine, the combination of a carriage, a vertical shaft discon- 30 nectably connected to said carriage, a horizontally arranged escapement wheel supported on said shaft, teeth mounted to move up and down on said escapement wheel, a coöperating abutment, and a key controlled actuator for said teeth.

5. In a typewriting machine, the combination of a carriage, a vertical shaft discon- 40 nectably connected to said carriage, a horizontally arranged escapement wheel sup- ported on said shaft, teeth mounted to move up and down on said escapement wheel, a coöperating abutment, printing key levers, and an actuator movable up and down by said levers and coöperative with said teeth.

6. In a typewriting machine, the combination of a carriage, a vertical shaft discon- 45 nectably connected to said carriage, a horizontally arranged escapement wheel sup- ported on said shaft, teeth mounted to move up and down on said escapement wheel, a coöperating abutment, a key controlled lever, and an actuator pivoted to said lever and movable up and down thereon for coöperation with said teeth.

7. In carriage feeding mechanism for typewriting machines, the combination of an escapement wheel provided with a circularly arranged set of headed pins movable trans- 55 versely of the plane of rotation of said wheel, an abutment coöperating with said pins, and a key controlled actuator for said pins.

8. In carriage feeding mechanism for typewriting machines, the combination of

an escapement wheel provided with a circularly arranged set of headed pins, an actuator for moving said pins transversely of the plane of rotation of said wheel, said pins being also adapted to rotate on their own axes, and an abutment coöperative with said pins.

9. In carriage feeding mechanism for typewriting machines, the combination of an escapement wheel provided with a circularly arranged set of headed pins movable trans- 75 versely of the plane of rotation of said wheel, an abutment coöperating with said pins, and a key controlled actuator for said pins, said pins being also adapted to cam said actuator out of their paths of rotation.

10. In carriage feeding mechanism for typewriting machines, the combination of an escapement wheel comprising a guiding portion and a supporting portion, pins longitudinally movable on said guiding portion 85 and normally engaging said supporting portion, an abutment coöperative with said pins, and a key controlled actuator for moving said pins longitudinally.

11. In carriage feeding mechanism for typewriting machines, the combination of an escapement wheel comprising a guiding portion and a supporting portion, pins longitudinally movable on said guiding portion and normally engaging said supporting portion, an abutment coöperative with said pins, a key controlled actuator for moving said pins longitudinally, and a cam device for insuring the return engagement of said pins with said supporting portion 100 after actuation by said actuator.

12. In carriage feeding mechanism for typewriting machines, the combination of an escapement wheel provided with relatively movable teeth, a coöperative abutment, an actuator, a key controlled lever to which said actuator is pivoted, a flat spring on said lever engaging said actuator, and a stationary stop normally coöperative with said spring.

13. In carriage feeding mechanism for typewriting machines, the combination of a carriage, an escapement wheel provided with teeth movable independently of said wheel, arresting means coöperative with said teeth, 115 means for controlling said teeth to permit step-by-step movements of the carriage, and a cam coöperative with said teeth during the return movements of said carriage to enable them to clear said arresting means.

14. In carriage feeding mechanism for typewriting machines, the combination of an escapement wheel provided with a circularly arranged set of movable pins, an abutment coöperative successfully with said pins to 125 arrest the carriage, a key controlled actuator for releasing said pins from said abutment, and a stationary device arranged adjacent

to said abutment and operative successively on said pins immediately prior to their co-operation with said abutment to insure the engagement of said pins with said abut-
5 ment.

Signed at the borough of Manhattan, city of New York, in the county of New York,

and State of New York, this 13th day of November, A. D. 1912.
